(57) **CLAIM**

The ornamental design for a plush teddy bear vase, as shown and described.

DESCRIPTION

FIG. 1 is a perspective view of a plush teddy bear vase.

FIG. 2 is a front elevational view thereof.

FIG. 3 is a rear elevational view thereof in a closed position.

FIG. 4 is a right side elevational view thereof.

FIG. 5 is a left side elevational view thereof.

FIG. 6 is a top plan view thereof.

FIG. 7 is a bottom plan view thereof; and,

FIG. 8 is a perspective view thereof in an open position.

The broken line showing of the flowers in FIG. 1 is for illustrative purposes only and forms no part of the claimed design.
